UNITED STATES PATENT OFFICE

114,769

DESIGN FOR A SMOKING STAND

Edward Schultz, Chicago, Ill., assignor to The Nagel-Chase Mfg. Co., Chicago, Ill., a corporation of Illinois

Application May 23, 1938, Serial No. 77,352

Term of patent 7 years

To all whom it may concern:

Be it known that I, Edward Schultz, a citizen of the United States, residing at Chicago, in the county of Cook and State of Illinois, have invented a new, original, and ornamental Design for Smoking Stands, of which the following is a specification, reference being had to the accompanying drawing, forming a part thereof—

Figure 1 is a front elevation, and Figure 2 is a top plan view, of a smoking stand showing my new design. The dominant features of my design reside in the parts shown in solid lines.

I claim:

The ornamental design for a smoking stand, as shown and described.

EDWARD SCHULTZ.
